UNITED STATES PATENT OFFICE.

NELSON TRACY MASH, OF CHICOPEE FALLS, MASSACHUSETTS.

ART OF FINISHING IMPERFECTLY-WOVEN CLOTH.

SPECIFICATION forming part of Letters Patent No. 350,008, dated September 28, 1886.

Application filed June 28, 1886. Serial No. 206,501. (No model.)

To all whom it may concern:

Be it known that I, NELSON TRACY MASH, of Chicopee Falls, in the county of Hampden, of the Commonwealth of Massachusetts, have 5 invented a new and useful Improvement in the art of Finishing Imperfectly-Woven Cloth; and I do hereby declare the same to be described as follows.

Cloth, especially that termed "cotton-flannel," that is to be napped and sheared in the process of completing it, is very liable to come from the loom with more or less imperfections, due to bad weaving, which, if the cloth is without further treatment, will, while it is being 15 subjected to the action of the napping-machine, cause holes to be torn in it.

To prevent such formation of holes is the object of my invention, in the carrying out of which I apply to the imperfect portions of the 20 woven cloth a layer of paraffine-wax, in a cold state, by rubbing or spreading the wax on the imperfections so as to cover them therewith, which having done I comb it in or upon the cloth by means of a steel comb, such as weavers 25 use.

In applying the wax to the cloth I prefer to make use of a stick of the wax, or a pencil of which the wax fills the bore as does the plum-bago or graphite of a common lead-pencil, as with such the imperfections, which are usually 30 long and narrow, can be waxed to advantage. Next I submit the cloth to the action of the napping-machine to raise a nap on it, and subsequently finish it by shearing it by means 35 usually employed after the raising of the nap on it by such napping-machine.

I claim—

The improvement, substantially as described, in treating cloth woven with imperfections, such consisting in covering the imperfect parts with paraffine-wax and combing it in by means of a weaver's comb, and next raising the nap by a napping-machine preparatory to shearing the nap and finishing it in the ordinary way.

NELSON TRACY MASH.
